(57) **CLAIM**

I claim the ornamental design for a table, as shown and described.

DESCRIPTION

FIG. 1 is an isometric perspective view of the table of this invention.

FIG. 2 is another isometric perspective view of the table positioned at a different angle.

FIG. 3 is a top plan view thereof.

FIG. 4 is a side elevation thereof; and,

FIG. 5 is a front or rear elevation thereof.

1 Claim, 5 Drawing Sheets

FIG. 1

FIG. 2

FIG. 3

FIG. 4
